UNITED STATES PATENT OFFICE.

JOHN W. FREE, OF WOODLAWN, PENNSYLVANIA.

TRANSFER APPARATUS.

Application filed July 27, 1925. Serial No. 46,205.

My invention relates to improvements in transfer apparatus. In Letters Patent of the United States No. 1,482,921, granted me February 5, 1924, I have described apparatus for taking sheets of rolled steel one by one from a pile and for feeding them to a tin-pot, where by coating they are converted into what is known to the industry as tin plate. My present invention has to do 10 with improvements on that apparatus.

In the accompanying drawings Fig. I is a view in side elevation, showing somewhat diagrammatically tin-pot feeding apparatus embodying my invention installed 15 for service. Fig. II is a view in end elevation of the same apparatus, looking from left to right, the tin-pot and its immediately associated parts being, however, omitted. Fig. III is a view to larger scale, showing in 20 vertical section a detail which in Fig. I is shown in side elevation. Fig. IV is a view corresponding to Fig. II, but to larger scale, and showing certain parts only, separated for the sake of clearness. Fig. V is a view 25 in plan from above of the structure shown in Fig. IV. Figs. VI and VII are diagrammatic views in plan and in side elevation, to illustrate more fully the operation of the parts included in Figs. IV and V.

Referring to Fig. I, the intake side of a tin-pot will be found, sufficiently indicated in dotted lines, at 1. Adjacent the tin-pot, on this its intake side is arranged a bosh 2, which, filled with water, carries submerged 35 within it, in the inclined position shown, a pack of rolled steel sheets S. These are the sheets which are to be taken one by one from the pack S, and delivered to the tin-pot, and according to established practice, thrust 40 edgewise into the bath of molten tin within the tin-pot. The sheets in the pack S lie in parallelism to the line along which in the operation of the apparatus they are thrust edgewise into the tin. The drawings show a 45 succession of guide plates 3, 4, and 5, and a succession of pairs of power-driven guide rolls 6, 7, and 8, each pair served by one of the said guides, and by these means, it will be understood, the successive sheets are advanced, in arched, approximately semi-circular course, from the bosh 2, on the right (Fig. I), to tin-pot 1, on the left.

My invention has to do with apparatus for taking the sheets one by one from the pack S and carrying them over the approx-

imately quadrant shaped guide plate 3 and introducing them at the forward edge into the bite between the pair of feed rolls 6. When once a plate has so been introduced between rolls 6, it is apparent without further explanation, that it will be carried forward by the feeding means indicated, from right to left, and at length thrust downward into the tin-pot. My further description, then, will be concerned with the handling of the sheet, from its removal from pack S to its introduction into the bite between rolls 6.

A shaft 9 (Figs. I, II and III) is rotatably carried at the ends of arms 10, of which there are two, extending adjacent the two sides of bosh 2. The arms 10 in turn are pivoted in the ends of arms 11 which swing on fixed pivots 12. Arms 11 are further provided with rollers 13, by which they 70 and the parts which they carry rest gravitationally upon cam disks 14 carried by a shaft 15.

From shaft 9 extend arms 16, of which preferably there are two for each bosh, and each arm 16 carries at its extremity a suction cup 17. Additionally, at its two ends shaft 9 carries crank arms 18, and these crank arms are connected by links 19 (telescopically extensible beyond a minimum length) 85 to crank disks 20, borne by a shaft 21. The crank arms 18 are additionally provided with rollers 22 which run on inclined tracks 23, and by these means shaft 9 and the parts which it carries are limited in the range of 90 turning under gravity and rest by their weight (when they are free to do so) upon tracks 23. During a portion of the rotation of crank disk 20 the rollers 22 engage the tracks 23, and roll down the tracks, and links 95 19 meanwhile elongate, as presently will be explained.

Shaft 21 rotates in synchronism with shaft 15, and in opposite direction. Shaft 15 is the main driving shaft of the machine, 100 and from it, through suitable interposed gearing, shaft 21 is driven. Manifestly, shaft 21 alternatively might become the drive shaft.

The crank disks 20, by a particular 105 shaping of the periphery, become cam disks also, and against their peripheries bear rollers 24, which turn idly upon studs borne by arms 10. Provision is made that always rollers 24 shall engage the cam surfaces of 110

disks 20. Conveniently, and as here shown, the parts are so arranged with respect to the vertical that the arms 10 with the parts they bear, tend always to swing under gravity 5 upon their pivotal supports in clockwise direction (Fig. I). The particular shape at the periphery of the cam disks 20, then, determines the swing of arms 10. Similarly, the whole structure under consideration, 10 with respect to the fixed pivots 12, rests by gravity through rollers 13 upon cam disks 14, and the particular peripheral shape of the cam disks 14 determines the swing of arms 11.

15 Arms 16, as has been said, carry suction cups 17, and, with Fig. I in view, it is to be observed that shaft 9 is situated approximately at the center of curvature of guide plate 3; that the arms 16 are in length approximately equal to the radius of curvature of the said plate 3; and that when the parts are in the position shown in Fig. I, the suction cups 17 stand adjacent the upper edge of the pack S of sheets, spaced at a 20 small interval from the upper inclined face of the pack, and that the plane in which the edges of the cups extend is a plane which is substantially parallel to the upper inclined surface of the pack S.

25 30 The minute construction and mounting of the arms 16 are shown in Fig. III. By means of pins 91 extending from shaft 9 and passing through elongate holes in the bearing blocks 161 by which the arms 16 are mounted, there is a small but sufficient range of independent movement. Otherwise, 35 the arms are responsive to the turning of shaft 9. The arms tend always to turn under gravity clockwise (Figs. I and III) 40 upon shaft 9. The arms are extensible to an accurately determined maximum. In Fig. III the numeral 16 is immediately applied to the extensible part, and in this figure the range of extension is indicated. The 45 arm is shown in full lines in its fully extended position, and its retracted position is indicated in dotted lines. The outward limit of extension is fixed by the abutment of the shoulder 162 with which the extensible member 16 is provided, upon the body 161. A 50 gravity latch 163 serves at proper time to secure the extended member 16 from retraction. A yoke 164 with down-turned ends 165, secured to the latch, serves, in cooperation with other parts, to raise the latch at 55 proper time. It is the extensible member 16 which immediately carries the suction cup 17.

Beginning with the parts in the position 60 shown in Fig. I, the suction cups travel in the following course: first they advance to the pack S, in a direction radial from the center of turning 9 and perpendicular to the plane of the surface of the topmost sheet, and they engage at their edges the topmost sheet. As they come to and preferably

shortly before they make engagement with the topmost sheet suction is exerted, in consequence of which from the moment of engagement the topmost sheet is carried by the cups in their further movement. After 70 such engagement has been made and such condition of suction has been set up, the cups recede in radial direction with respect to the center of turning 9. In so doing they swing the topmost sheet, which still rests on its 75 lower edge within the bosh, separate it from the underlying sheets of the pack, and bring it at its upper edge to a position of approximate tangency to the curve of guide plate 3. The suction cups then swing upward in a 80 curved path (shaft 9 is the center of turning) to the elevated position indicated in dotted lines in Fig. I. In so swinging upward the cups drag the engaged sheet over the surface of guide plate 3 and thrust the 85 forward edge of the sheet into the bite between the pair of guide rollers 6. The guide rolls 6 then engaging the sheet, carry it forward. Immediately when the sheet has 90 so been carried to and delivered up to the guide rolls 6, suction is relieved, and instead a condition of pressure is set up within the cups. Engagement of the cups with the sheet is broken and the cups then recede somewhat farther in radial direction with 95 respect to the center of turning 9. They then swing downward again in curved path, on the same center of turning, and so come again approximately to the position shown in Fig. I. This completes the cycle. 100

The instrumentalities described effect the movement described in the following manner. Shaft 15 with its cams 14 turns clockwise; shaft 21 with its cams 20 turns anti-clockwise, and the two shafts make synchronous revolution. The parts being in the position shown in Fig. I, it will be observed that for something more than half a revolution there will be no swinging of arms 11 upon their pivots 12, and that during that interval the arms 10 will be sustained by the arms 11, as though on fixed pivots. With attention upon the engagement of rollers 24 upon cam disks 20, it will be observed that during this half revolution and more the rollers will traverse the edges $a-b-c-d$ of the disks. As the points of engagement of rollers 24 upon the cam disks 20 advance along the edges of the disks beyond the points a and toward the points b , arms 10 will swing clockwise, and arms 16 borne by shaft 9 will be carried from left to right. Because of engagement of rollers 22 upon tracks 23, this left to right advance of the cups will be in right-line course, perpendicular to the surface of the top sheet in pack S. Links 19, it will be remembered, are extensible from a minimum length, and it is because they are so extensible that the turning of the disks 20 anticlockwise while 110

105

110

115

120

125

130

the points of engagement of rollers 24 with the disks advance from *a* to *b*, that the described right-line advance of the suction cups is possible. At this time the arms 16 are downwardly inclined and are consequently extended under gravity. The latches 163, however, are, in consequence of the engagement of the yokes 164 upon the tracks 23, withdrawn.

10 As the cam disks 20 turn and as the rollers 24 in engagement upon the cam disks, progress from points *a* and *b* (and as in such progression the arms 10 swing clockwise) the suction cups 17 come to engagement upon 70 the top sheet of pack S. The precise moment of this engagement will vary, as the thickness of pack S varies. In the further swing of arms 10 the arms 16 collapse automatically, so far as may be necessary. The fact 75 that at that time latches 163 are withdrawn, makes possible this necessary shortening of arms 16.

At the moment when the cups come to engagement upon the topmost sheet of the 25 pack, or preferably slightly before that moment, a condition of suction is, by instrumentalities presently to be described, created within the cups.

The continued turning of disks 20 causes 30 the portion of the peripheries from *b* to *c* to come beneath rollers 24, and in consequence, there will be reversal of movements: the arms 16, to the extent that they have collapsed, will lengthen again to their maximum 35 extension, and then arms 16 with their cups 17 will recede again, moving in right-line direction. But the recession will not be all the way to the point from which advance began, for, as will be observed, the point *c* is 40 remote from the center of turning a somewhat less radial distance than the point *a*.

When the point *c* has been reached the 45 links 19 which at first lengthened have shortened again, and come to minimum length, and, while (because the portion *c*—*d* of the periphery of disks 20 is an arc of a circle concentric with the center of turning) the shaft 9 will now continue on a stationary axis, the further anti-clockwise turning of 50 disks 20 will, through links 19 and cranks 18 effect the turning of shaft 9 on its axis and the consequent upward swing of the cups 17. Immediately on the rise of arms 16 the latches 163, released by separation 55 from tracks 23 will descend by gravity and lock arms 16 in their position of maximum extension. The upward swinging of arms 16 will be through a range of approximately 90°, to the position shown in dotted lines, 60 in Fig. I, where, having dragged the engaged sheet upward over guide plate 3, the cups have delivered the forward edge of the sheet to the bite between the pair of guide rolls 6. At that point suction is relieved and a 65 condition of pressure is created within the

cups, insuring the immediate break of the engagement of the cups upon the sheet.

Mention has been made of the play permissible between the arms 16 and the shaft 9 which, by turning, swings them. This play 70 has value, for thus, at the moment of delivery of the sheet to the rolls 6, the arms 16 may through a sufficient interval swing in response to the pull exerted by rolls 6 75 through the in-fed sheet. It is necessary, in adapting the machine to different sheet-lengths, to change from time to time the speed of shaft 9 relatively to that of rolls 6, and this small interval, during which the arms 16 may swing in free response to the 80 pull of rolls 6, makes possible such change in relative speeds, without disturbance. Furthermore, with this provision, small irregularities of material have no effect, to 85 disturb normal operation.

The cam disks 14 hitherto have sustained the arms 11 in elevated position. When the 90 cups have risen to the top of their swing, the point of engagement of cams 14 with rollers 13 (the disks turning clockwise) has advanced to *m*. Further turning of disks 14 causes arms 11 to swing under gravity downward through a small range. At the same time the turning of disk 20 has caused the points of engagement with rollers 24 to 95 advance from *d* to *e* (with increase of effective radius). The result is that shaft 9 is shifted in its position: it drops through a slight interval, and moves slightly to the left, to a center of turning indicated by 100 the small circle *x*.

The axial position of shaft 9 then remains fixed for nearly half a rotation, and during this time the disks 20 continue to turn, and arm 16 swing under gravity, rotating shaft 105 9 as they descend. Just before the limit of descent is reached the turning cam disks 14 swing arms 11 upward, and in consequence the shaft 9 is again elevated slightly. Also, just before the limit of downward swing of 110 arms 16 is reached the yokes 163 engage, through their downward extending ends 164, the tracks 23, raising the latches 162. Thus the parts come again to the position shown in Fig. I, and the cycle is completed. 115

It remains to describe the means for creating and relieving suction within the cups, and this in correlation to the machine parts already described.

A pump cylinder 25 is mounted in vertical 120 position in a rigid part of the structure. The chamber within the cylinder and beneath the piston is by flexible hose connected with the interior of the cups. Fig. III shows one of the cup-bearing arms 16 125 in section. The flexible connection is made immediately to the duct 26 in the arm, which, as shown, leads to the cup.

The piston rod 36 of the piston within the cylinder 25 is secured to the cross piece 130

35 of a yoke, whose depending arms 34 carry a clevis 27, in which is pivoted the end of a beam 28. This beam 28 is swung on a fulcrum 29 which is fixed in the frame 5 of the machine. It extends beyond the fulcrum point. This beam is alternately swung, first clockwise and then anti-clockwise. At its farther end the beam is engaged by a cam 37 which is borne by shaft 21; and, at 10 a point intermediate the fulcrum and the end pivoted in clevis 27, a contractile spring 33 is secured to the beam. The tension of this spring tends always to raise the beam. The cam 37 is so proportioned that, for 15 something less than one half of a revolution of shaft 21, the beam is by it swung anti-clockwise on its pivot, and the piston within cylinder 25 is held at the lower end of its range of traverse, and no suction effect 20 is exerted. During the remainder of the revolution of shaft 21, the beam is responsive to the tension of spring 33, and the spring is effective to swing the beam clockwise, and to effect suction. In Fig. VII the 25 parts which have just been described are, in order to distinguish them from parts which remain to be described, shown in broken lines. As I have already said, co-ordination is such that suction becomes effective as the cups 17 advance to engage the top sheet of pack S. The effective strength of the spring may be varied by the provision of such an adjustable anchorage as is indicated at 32.

35 I further provide that initially the suction which the cups 17 exert shall be relatively weak (although adequate) and that under such relatively weak suction the engaged sheet shall be swung aside and separated from the pack, and that when the sheet has been swung aside and brought to position of approximate tangency to the curve of guide plate 3, then, before the upward swing of the cups begins, the suction 40 shall be strengthened. To this end spring 33 is carried on the cross-bar 31 of a yoke whose downward reaching arms 30 terminate in clevises 38. In these clevises are pivoted the outer ends of levers 39 (one only is shown, but it will be apparent that a pair is requisite), pivoted at 40 in a stationary part of the structure. The levers 39 are engaged by cam disks 41, on shaft 21, and the cams 41 are so shaped that during 45 part of a rotation of shaft 21 cross-bar 31 is raised, and the effective tension of spring 33 consequently increased. The cams 37 and 41 are so proportioned and so particularly located that, during a portion of 50 the time when cam 37 is inactive and beam 28 is responsive to the tension of spring 33, cam 41 is effective, to increase the spring tension. Lever 39 and its operating cam 41 are in Fig. VII shown in full lines. By 55 such provision the suction first exerted is

mild, and, then, at the moment when firmer hold is required of the cup upon the sheet, the suction is increased.

The value of so employing first a weak and then a strong suction may be made plain in a few words. The sheets which lie in a pack within the bosh lie in contact, with films of water between. Each sheet individually has little strength to resist distortion. I have found that the localized condition of 75 suction created within the cup and upon the topmost sheet, if it be relatively great in intensity and suddenly applied, will in frequent instances distort both the topmost sheet and the underlying sheet as well, with 80 the result that two sheets may be swung aside together and carried forward toward the tin-pot. But if the degree of suction be light, the distortion will be inappreciable 85 and the effect of the suction will be confined to the topmost sheet; one sheet and no more will be swung aside and carried forward. The actual degree of suction will, in the practice of my invention, be such that its effect will be confined to the topmost sheet; 90 but since when so limited, although sufficient to swing the topmost sheet aside and out of contact with the next underlying sheet, it may still be insufficient to hold the sheet in the ensuing step of dragging it upward over 95 guide 3 to rolls 6, in order certainly to hold the sheets secure at this time, I provide that the degree of suction shall be increased within the cups after the sheet has been swung aside and before the dragging of the sheet 100 upward begins.

In the particular shaping of the cup I make further provision, preventive of the warping of the sheet under suction and the consequent danger of carrying two adhering 105 sheets (termed a "double"). The body of the cup, formed ordinarily of rubber, is secured to a suitably disposed surface upon arm 16 by means of a nut 42. This nut is externally bulged or rounded so that, while 110 affording sufficient space within the cup, it rises centrally almost to the plane in which the cup when under suction engages the sheet. This domed nut offers its body, to prevent any appreciable local warping of 115 the sheet by suction. The nut, or the stud which carries it, is ported to afford communication with the pump cylinder 25.

Returning to the matter of the particular shape of cam 37, I call attention to the steep rise 371 in its face (Fig. VII) and, bearing in mind that in operation the cam turns anti-clockwise as here seen, it will be perceived that the effect of this abrupt rise will be suddenly and powerfully to drive downward the piston within cylinder 25, changing the condition of suction within the cup to a condition of pressure, and so certainly and at the proper instant to break the suction hold of the cup upon the sheet. This 125 130

occurs at the moment the cup comes to its highest point (shown in dotted lines in Fig. I), when the raised cups have carried the sheet to engagement by the rolls 6.

5 The bosh 2 is ordinarily full of water, and, accordingly the cups 17 plunge beneath and suctionally engage the sheets under water. It follows that cylinder 25 and the hose connection and the cups when in service are full 10 of water or substantially so. I find that under such conditions the stroke of the piston would, but for preventive measures, act with undesired violence in the engagement of the cup upon the sheet. In order to cushion this 15 engagement I form in the cylinder wall a port 43 opening either directly or through another body of liquid to the open air, and in this opening I place a pet-cock 44. This pet-cock I adjust, until I get precisely the 20 intensity I desire in the engagement of the cup with the sheet. The port 43 controlled by the pet-cock is at all times during the course of the operation open. Since, as has been said, the cups and the hose and the cylinder 25 are at all times substantially full of water, reversal of the stroke of the piston has immediate effect, tending to create within the cups a condition of pressure and therefore immediately releasing them from 30 their engagement upon the sheet.

I claim as my invention:

1. In apparatus for conveying sheet material a movable member, a suction cup borne 35 by said member, means for creating within the cup a condition of suction, means for shifting the cup while such condition of suction is maintained within it, means operating in sequence upon the means last named 40 for exhausting air from the cup when the cup already is in engagement upon the material.

2. In apparatus for conveying sheet material and in combination with a support for material to be conveyed, a movable member, 45 means for moving said member first in a direction perpendicular to the surface of sheet material borne on said support, and, sequent thereon, in a direction transverse to the initial direction of motion, a suction cup borne 50 by said member, means for maintaining within the cup a condition of relatively weak suction during its initial movement and of relatively strong suction during its sequent 55 movement aforesaid.

3. In tin-pot feeding apparatus, the combination with a tin-pot, of a bosh arranged adjacent the tin-pot at its intake end, means 60 for sustaining within the bosh and in inclined position a pack of sheets, conveying means adapted to carry to the tin-pot sheets fed from the bosh, and means for feeding sheets one by one from the bosh to said conveying means, such means including a laterally shifting and upwardly swinging member, a suction cup borne by the member

last named, and means for maintaining within the cup a condition of relatively weak suction during the lateral shift of the cup-bearing member and a condition of relatively strong suction during the upward 70 swing of said member.

4. In tin-pot feeding apparatus, the combination with a tin-pot, of a bosh arranged adjacent the tin-pot at its intake end, means 75 for sustaining within the bosh and in inclined position a pack of sheets, conveying means adapted to carry to the tin-pot sheets fed from the bosh, and means for feeding sheets one by one from the bosh to said carrying means, such feeding means including a rotary shaft, extending in parallelism to the surface of a pack of sheets within the bosh, means for shifting said shaft toward and away from a pack of sheets within the bosh, means for effecting intermittent rotation 80 of said shaft, an arm borne by said shaft and rotatable through a limited range independently of shaft rotation, a suction cup borne by said arm, and means for alternately creating and destroying a condition 85 of suction within the cup.

5. In tin-pot feeding apparatus the combination with a tin-pot, of a bosh arranged adjacent the tin-pot at its intake end, means 90 for sustaining within the bosh a pack of sheets, conveying means adapted to carry to the tin-pot sheets fed from the bosh, such conveying means including a pair of feed rolls, and means for carrying sheets one by one from the bosh to the feed rolls, said carrying means including a suction cup and including also a lost-motion device, whereby on engagement by said rolls the sheet is unrestrained in its response to the action of the rolls upon it. 100

6. In tin-pot feeding apparatus the combination, with a tin-pot and with a bosh arranged adjacent the tin-pot at its intake end and adapted to carry in inclined position a pack of sheets to be tinned, two horizontally 110 extending oppositely and synchronously rotating shafts arranged adjacent one another and adjacent said bosh, a pair of arms swinging on fixed pivots, a pair of cams borne by one of said shafts and adapted to swing said arms in vertical planes as the shaft rotates, a second pair of arms pivoted to the first pair of arms, a pair of cams borne by the second of said shafts and 115 adapted to swing in vertical planes the arms of the second pair, a third shaft borne by said second pair of arms, means for rotating the last named shaft in response to the turning of one of the two shafts previously mentioned during a portion of a revolution of the latter, the said shaft being oppositely rotatable under gravity, an arm extensible under gravity borne by the third shaft named above and provided with a latch 120 adapted to lock said arm in extended position. 125

tion, means for shifting said latch in response to the turning under gravity of said third shaft and of the said arm which it carries, a suction cup borne by said arm, and means for creating a condition of suction within said cup.

7. In apparatus for conveying sheet material, a movable member, a suction cup borne by said member, a pump cylinder containing a piston, fluid communication between said cup and said cylinder, a spring, means for bringing the tension of the spring to bear upon the piston within the cylinder, and means for increasing while the spring is in action its effective tension upon said piston.

8. In apparatus for conveying sheet material, a movable member, a suction cup borne by said member, a pump cylinder containing a piston, fluid communication between said cup and said cylinder, a rotary shaft, means operated by said shaft in its rotation for shifting said movable member, a cam borne by said shaft, a vertically swinging beam intermittently engaged by said cam, connection between said beam and the piston within said cylinder, a spring anchored in a vertically movable support and engaging said beam, a second cam borne by said shaft, and a lever engaged by said second cam and engaging the support for said spring.

shaft in its rotation for causing the spring 25 to exert its tension upon said piston, first with minor and then with major force.

9. In apparatus for conveying sheet material, a movable member, a suction cup borne by said member, a vertically standing pump cylinder containing a piston, fluid communication between said cup and the chamber in said cylinder beneath the piston, a rotary shaft, means operated by said shaft in its rotation for shifting said movable member, a cam borne by said shaft, a vertically swinging beam intermittently engaged by said cam, connection between said beam and the piston within said cylinder, a spring anchored in a vertically movable 40 support and engaging said beam, a second cam borne by said shaft, and a lever engaged by said second cam and engaging the support for said spring.

In testimony whereof I have hereunto set 45 my hand.

JOHN W. FREE
